DIAPER

Filed Nov. 19, 1948

2 Sheets-Sheet 2

Fig. 2

A technical drawing showing a vertical seam or fold line. The left side of the seam features a series of circular holes, with callouts labeled 19 and 21 pointing to them. The right side of the seam has a series of rectangular notches, with callouts labeled 14, 25, and 26 pointing to them. A large arrow at the top right points towards the seam, labeled with the number 10.

be made in the embodiment hereinbefore shown and described, it is to be understood that all matter herein is to be interpreted merely as illustrative and not in a limiting sense.

I claim:

A diaper comprising a length of a sheet material having portions of its opposite ends of a uniformly reduced width and adapted to be folded along its transverse center to provide a double thickness, the double portion of greatest width being adapted to be encircled about the back and sides of an infant and the end portions of reduced width to cover the abdomen of the infant, sets of snap fastener parts spacedly secured along the opposite ends of the line of fold at the outer side of the outer portion of the material, and a single cooperative snap fastener part secured at

10

each corner of the inner side of one of said reduced end portions for selective engagement with the first snap fastener parts, the other of said reduced end portions having an opening in each of its corners and adapted to be engaged with the last named snap fastener parts and the selected of the first snap fastener parts.

WILLIE C. BURKE.
